CLAIM

USPC **D14/485**

The ornamental design for a display panel or screen or a portion thereof with a graphical user interface, as shown and described.

(58) **Field of Classification Search**

DESCRIPTION

USPC D14/485–95, 486
CPC .. G06F 3/0481; G06F 3/0482; G06F 3/04812; G06F 3/04817; G06F 3/0484; G06F 3/0485; G06F 3/048; G06F 3/0487; G06F 3/0488; G06F 3/0483; G06F 3/0486; G06F 3/0489; G06F 3/0486; G06F 3/04842; G06F 3/04845; G06F 3/04847

See application file for complete search history.

The patent or application file contains at least one drawing executed in color. Copies of this patent or patent application publication with color drawing(s) will be provided by the Office upon request and payment of the necessary fee.

FIG. 1 is a front view of a first embodiment of a display panel or screen or a portion thereof with a graphical user interface showing my new design; and, FIG. 2 is a second embodiment thereof.

The outermost even-dash broken lines showing a display panel or screen, or a portion thereof, form no part of the claimed design. The remaining broken lines shown in FIGS. 1 and 2 are part of the claimed design.
